ELECTRON TUBE

Paul Georges Chevigny, Paris, France, assignor
to Federal Telephone and Radio Corporation,
New York, N. Y., a corporation of Delaware

Application January 26, 1946, Serial No. 643,787

16 Claims. (Cl. 250—152)

1

This invention relates to electron beam-producing apparatus, particularly of the type suitable for use as electronic distributors, and to the method of manufacturing same.

Electronic distributors for distributing energy to a plurality of channels, usually to selected ones of said channels, have been suggested for use in various multiplex systems such as for example, in the copending application of E. M. Deloraine for "Communication system," Serial No. 628,613, filed November 14, 1945. In the Deloraine system, signals are translated into amplitude-modulated pulses. These amplitude-modulated pulses are given a predetermined amount of delay corresponding to the channel to which they are directed. An electronic distributor is employed to distribute these pulses to the selected channel, the amount of delay determining the channel.

The distribution is accomplished by providing in said distributor, means for rotating an electron beam, as in a cathode ray tube, and mounting in the circular path of the beam, a plurality of target elements which are connected to different channels. Normally the beam is cut off as by applying a suitable cut-off voltage to the control element of the distributor. As the beam-rotating means operates to set up varying fields which would rotate the beam, signals arrive and are impressed upon the control element to raise its potential above cut off and cause the beam to flash on. The instantaneous fields then existing by virtue of the operation of the beam-rotating means, direct the beam to one of the target elements and produce a pulse in the channel associated with said element. Since the beam-rotating fields vary continuously and cyclically, the particular target element effected by a given pulse depends on the time of arrival of the pulse or, stated another way, depends on the amount of delay of the pulse with respect to a given reference.

Where a limited number of channels are employed and therefore a limited number of target elements are required within one distributor, as for example, a hundred, it is feasible to arrange the target elements in a single circle which is scanned by the rotatable electron beam. Where, however, greater numbers of such elements are required, this arrangement becomes impractical.

An object of the present invention is the provision of improved electronic beam-producing apparatus of the type hereinabove described.

Another object is the provision of such ap-

2

paratus having a novel arrangement of the target elements.

Another object is the provision in such apparatus of a very large number of target elements.

Another object is the provision of such an apparatus in which the target elements are separated from each other by shields to minimize interference or "cross-talk" between the various channels.

Further objects are the provision of an improved method for making electronic beam-producing apparatus of the general type referred to hereinabove.

Other and further objects of the present invention will become apparent and the invention will be best understood from the following description of embodiments thereof, reference being had to the drawings, in which:

Fig. 1 is a diagrammatic representation of an electron beam-producing apparatus in accordance with my invention;

Fig. 2 is a plan view of the arrangement of the target elements during one step in the process of manufacturing the apparatus of Fig. 1;

Fig. 3 is a plan view of one of the shields interposed between the target elements in the apparatus of Fig. 1;

Fig. 4 is a diagrammatic representation of a modified form of apparatus embodying my invention; and

Fig. 5 is a similar view of another modification.

Referring now to Fig. 1, the apparatus there illustrated, includes a form of cathode ray tube 1 having an envelope 2 within which is mounted toward one end thereof a conventional type of electron gun 3 including a control element or grid 4 to which energy, in the form of pulses, which are to be distributed in accordance with their time of arrival, are fed over line 5. At a distance from the gun 3, there are arranged conventional horizontal and vertical deflecting plates 6 which are connected over a pair of lines 7 to a two-phase generator 8 which serves to produce a rotation of the electron beam 9 which passes between said deflecting plates when an incoming pulse arrives along line 5. The two-phase generator 8 may be synchronized from any suitable source. At the expanding portion of the tube envelope 2, there is arranged a toroidally-shaped spiral coil 10 through which current is fed to produce a magnetic field which curves the electron beam 9 as it passes through, the strength of this field determining where along the length of the envelope the beam 9 will impinge upon the

hereinafter-described target elements. Current is supplied to toroidal-deflecting coil 10 by a stepped saw-tooth generator 11 which produces a saw-tooth output composed of steps, as shown in wave-form 12, to change the layer or tier of target elements upon which the beam impinges. The saw-tooth generator 11 is synchronized with the two-phase generator 8 over line 13, so that after each complete rotation of the beam produced by the two-phase generator 8, generator 11 increases the energy supplied to coil 10 by a single step.

The target elements may be arranged in the form of a plurality of rows or tiers 14 longitudinally spaced from each other along the tube envelope, with a plurality of annular metallic shields 15 interleaved between successive tiers. Each of the tiers consists of a plurality of metallic target elements 16 which elements may be in the form of short wires or rods which extend radially and are circumferentially spaced from each other and sealed in the glass wall of the envelope 2. The construction of this portion of the cathode ray tube may be best understood from a description of the method of making it.

Referring now to Fig. 2, a wire 17 in the form of a circle having a diameter greater than the diameter of the cathode ray tube envelope at which the target elements are arranged, has welded thereto, at spaced intervals, wire elements 18 which are somewhat longer than the target elements 16 but which are subsequently cut down as will be described hereinafter to leave portions which become the target elements 16. The short wires 18 are radially arranged and circumferentially spaced along circular wire 17. A large number of wires may be so arranged as for example, a hundred. The assembly 19 thus produced permits handling of the wires 18 as a single unit. As many assemblies 19 are provided as there are to be tiers of target elements in cathode ray tube 1. In the embodiment illustrated, there are ten tiers. A similar number of shields 15 are also provided. The shields 15 consist of flat disks, as illustrated in Fig. 3, each having a large central opening. The disk shields 15 and the assemblies 19 are alternately stacked one above the other with annular glass rings in between. A high frequency coil or other heating means is employed to heat the glass as for example, preferably by inducing a high frequency current in the disk shields 15, which serves to fuse the glass between the disk shields as well as around the assemblies 19. After the glass has been well fused about the disk shields 15 and the elements 18, it is gradually allowed to cool. The stacking of the assemblies 19 and shields 15 is so made that each of the circular wires 17 and the outer portion of the short wires 18 protrude beyond the disk shields 15. The circular wires 17 and the outer portions of the wires 18 are next cut off, thereby leaving the target elements 16 sealed through the glass rings 20. The disk shields 15 and the longitudinal wires 18 are preferably made of an alloy having the proper coefficient of expansion so that when subjected to heat, the seal between these and the glass will not be broken. Various types of chrome-iron alloys are known for this purpose, such as for example, that known by the trade name of "Kovar." The stack of disk shields and assemblies is then sealed to the rest of the tube envelope, as depicted in Fig. 1 toward the end thereof opposite the electron gun, with an end piece 21 of glass sealed to one end 22 of the stack

and the other end 23 of the stack sealed to an enlarged portion 24 of the envelope.

In the operation of the apparatus of Fig. 1, the strength of the magnetic field produced by the toroidal coil 10 may be initially sufficient to bend the beam 9 so that it is directed toward the first row of target elements nearest end 22 of the stack. The beam is then rotated for one complete revolution by means of the deflecting plates 6 actuated by the two-phase generator 8. Upon the completion of this single complete revolution of the beam, the saw-tooth generator operates to increase the energy supplied to coil 10 and causes the beam to impinge on the second row of target elements. The beam is then rotated for one complete revolution on the second row, whereupon another step increase in energy is applied to the toroidal coil 10 which shifts the beam to the third row of target elements from end 22. This is continued until the beam has scanned all the target elements of each row up to the end 23 of the stack whereupon the energy supplied to the coil 10 abruptly drops as shown in wave-form 12, thus redirecting the beam toward the first row of target elements at end 22 of the stack.

In the embodiment of Fig. 4, the use of the magnetic coil 10 is dispensed with by making the target elements 25 of gradually increasing length from end 23 progressively toward end 22 of the stack. The disk shields 26 are likewise of progressively increasing length, this being accomplished in the embodiment illustrated by welding to the inner ends of the disk 26 additional disks in which the central opening is of progressively decreasing diameter, from end 23 toward end 22 of the stack.

The apparatus of Fig. 4 also includes the electron gun 3 with control grid 4 and deflecting plates 6. The grid 4 is controlled by the signal 40 coming in over line 5 and the deflecting plates 6 are supplied with two-phase voltages from the two-phase generator 8 to produce a rotation of the beam. To move the beam from row to row of target elements, the stepped saw-tooth generator 11 is also employed but it is arranged to feed the two-phase generator with periodically stepped voltages so that the output of the two-phase generator is periodically increased, thereby producing an increased deflection of the beam 50 9 in its circular path so as to shift the beam from row to row of the target elements.

In the embodiment of Fig. 5, the electromagnetic field coil 10 is also dispensed with and the deflecting plate 6 and the electron gun 3 may be 55 controlled as illustrated in Fig. 4. The shields 23, together with their added disks 27, are similar to those in Fig. 4 and the gradually increasing length of the target elements measured radially from the center of the tube increase progressively 60 as do the lengths of the target elements 25 in Fig. 4. However, at the inner end of each of the target elements 28, there is an additional portion 29 bent at right angles and extending longitudinally of the tube substantially parallel to the 65 longitudinal axis thereof, the end 30 of each of said portions 29 facing the beam 9 and being adapted to be impinged upon by said beam. All of the ends 30 define a curve, all points of which are equi-distant from the center of the deflecting 70 plates 6 so that the beam travels an equal distance to any of the rows of the target elements.

The beam 9 rotates in the embodiment of Fig. 5, as it does in the other embodiments, and as, in the embodiment of Fig. 4, the radius or diameter of the circle made by the end of the beam

is varied to move the beam from one row of target elements to the next.

While I have described the beam as moving from row to row of target elements beginning near end 22 and moving toward end 23 of the stack, it will be obvious that the beam may move in the opposite direction, namely, from near end 23 toward end 22.

Furthermore, while I have described the apparatus of Figs. 1-5 as being used to distribute energy from one source to a plurality of loads, it will be apparent that it may be used for various other purposes. For example, such apparatus may be used as a pulse generator by having the beam continuously on and connecting all the target elements together to a common line. As the beam 9 sweeps from target element to target element, pulses will be produced in said line and a large number of pulses will be thus produced at each complete travel of the beam from element to element and from row to row. Various other uses will occur to those versed in the art from the hereinabove description and from the description of the aforementioned application of E. M. Deloraine.

Accordingly, while I have described above the principles of my invention in connection with specific apparatus, and particular modifications thereof, it is to be clearly understood that this description is made only by way of example and not as a limitation on the scope of my invention as defined in the accompanying claims.

I claim:

1. Electron beam-producing apparatus comprising means for producing an electron beam, a plurality of rows of target elements arranged in the path of said beam, each row consisting of a plurality of target elements spaced in a plane transverse to the plane along which the rows are spaced, and beam-deflecting means for deflecting the beam to impinge upon the target elements.

2. Electron beam-producing apparatus according to claim 1 further including shield means in the form of disks interposed between successive rows of target elements.

3. Electron beam-producing apparatus comprising means for producing an electron beam, a plurality of rows of target elements adapted to be impinged upon by said beam, each row consisting of a plurality of target elements arranged in the form of a circle, and means for deflecting the beam to impinge upon the target elements of each of said rows.

4. Electron beam-producing apparatus comprising an envelope, an electron gun positioned toward one end of the envelope for producing an electron beam, a plurality of rows of target elements supported from the wall of the envelope at longitudinally-spaced intervals thereon and approaching the other end thereof, each of said rows of target elements consisting of a plurality of target elements arranged in the form of a circle, means for producing a circular sweep of the electron beam, and for varying the angle of deflection of the beam from the path it would take if undeflected so as to determine the row of target elements upon which the beam impinges.

5. Electron beam-producing apparatus according to claim 4 further including a plurality of disks having central openings therein and serving as shields, sealed into the envelope between the rows of target elements.

6. Electron beam-producing apparatus according to claim 4 wherein said target elements are in the form of short wires sealed through the

envelope and extending radially of the longitudinal axis of the envelope, said wires being circumferentially spaced.

5 7. Electron beam-producing apparatus according to claim 4 wherein said target elements are in the form of short wires sealed through the wall of the envelope and extending radially of the central longitudinal axis thereof, said target elements being circumferentially spaced, further including shielding means interposed between the rows of target elements, said shielding means consisting of flat disks sealed through the envelope wall and having central openings therein.

15 8. Electron beam-producing apparatus according to claim 4 wherein said last-mentioned means includes an electromagnetic toroidal coil arranged outside the envelope between the electron gun and the target elements, and means for supplying to said coil energy periodically varying in small abrupt steps.

20 9. Electron beam-producing apparatus according to claim 4 wherein said target elements are in the form of short wires sealed through the envelope and extending radially of the central axis thereof with the target elements of each row being circumferentially spaced from each other, the target elements of each successive row being progressively longer than those of the preceding row.

25 10. Electron beam-producing apparatus according to claim 4 wherein said target elements each consist of a wire having one portion thereof sealed through the glass envelope and the other portion thereof extending substantially parallel to the longitudinal axis of the envelope with the sealed portions extending radially of said axis, and the sealed portions of the target elements within each row being circumferentially spaced from each other, and the sealed portions of each target element in succeeding rows being progressively longer, the portions parallel to the longitudinal axis being also progressively longer in each succeeding row so that the ends of said last-mentioned portions are all substantially equidistant along the deflected beam.

30 11. An electron distributor comprising a cathode ray tube including an envelope, means for producing an electron beam within said envelope, a plurality of annuli arranged transversely with respect to the beam path, a plurality of target members arranged along the path of said beam and each forming part of a respective one of said annuli, beam deflecting means associated with said beam producing means for producing a circular sweep of the electron beam, and means including a stepped saw-tooth generator for varying the deflection of the beam from the axis about which it sweeps to cause it to impinge upon the various target members.

35 12. An electron distributor according to claim 11 wherein said last-mentioned means includes an electromagnetic toroidal coil arranged outside the envelope between the electron gun and the target members, said generator being coupled to said coil for periodically varying the energy supplied to said coil in small abrupt steps.

40 13. An electron distributor according to claim 11, wherein said beam deflecting means includes two pairs of oppositely-disposed spaced deflecting plates between which said beam passes, the energy supplied to both said plates being controlled by the stepped saw-tooth generator.

45 14. An electronic distributor including a cathode ray tube having an envelope, an electron gun positioned toward one end of the envelope

for producing a narrow, electron beam, a plurality of rows of target elements supported from the wall of the envelope at longitudinally-spaced intervals thereon and approaching the other end thereof, each of said rows of target elements consisting of a plurality of target elements arranged in the form of a circle, the beam being so narrow that it is adapted to impinge substantially entirely on one of said target elements at a time, means for producing a circular sweep of the electron beam, and means for varying the angle of deflection of the beam from the path it would take if undeflected so as to determine the row of target elements upon which the beam impinges.

15. An electronic distributor according to claim 14 wherein said means for varying the angle of deflection of the beam includes a toroidal coil arranged adjacent the path of the beam to set up a toroidal electromagnetic field thereabout, and a stepped saw-tooth generator supplying energy to said coil.

16. An electronic distributor according to claim 14 wherein said means for producing a circular sweep of the electron beam includes two pair of spaced deflecting plates arranged at right angles to each other and between which the beam

passes, and a two-phase generator coupled to said deflection plates to produce a circular sweep of the beam, and wherein said means for varying the angle of deflection of the beam includes a stepped saw-tooth generator controlling the magnitude of the output of said two-phase generator.

PAUL GEORGES CHEVIGNY.
